Primary Examiner — T Chase Nelson(74) Attorney, Agent, or Firm — Shook, Hardy and Bacon L.L.P.CLAIM

The ornamental design for a shoe, as shown and described.

DESCRIPTION

FIG. 1 is a side view of a shoe showing my design; FIG. 2 is a front perspective view thereof; and, FIG. 3 is a rear perspective view thereof.

The long-and-short broken lines form an unclaimed boundary around at least a portion of the claimed subject matter, and form no part of the claim. The even-length broken lines, which show the remainder of the article, are directed to environment, represent unclaimed subject matter, and form no part of the claimed design.
